UNITED STATES PATENT OFFICE

CHARLES H. CURTIS, OF WHEATRIDGE, COLORADO

VENDING MACHINE

Application filed December 27, 1927. Serial No. 242,569.

My invention relates to vending machines, and more especially to vending machines in which the merchandise handled is wrapped in packages, or enclosed in boxes or cartons. 5 The object of my invention is to provide a vending machine that is simple and positive in operation, rugged in construction, and which is cheap to manufacture.

A further object is to provide a vending 10 machine which is difficult or impossible to rob without partial destruction of the machine.

A further object is to provide a vending machine in which the merchandise is visible, so that not only the purchaser but also the 15 service man may see at a glance the amount as well as the kind of stock still held by the machine.

A further object is to provide such a machine that is simple and easy to service, so 20 that the money may be collected and a new stock of merchandise installed with a minimum of time and trouble.

I accomplish the above objects by providing a machine in which, in each unit, but one 25 article at a time is delivered by the movement of the carriage for that unit, which is normally prevented from making the complete delivery movement by one or more triggers contacting against a locking shoulder, 30 the proper coins, when in place, acting to raise the triggers to clear the locking shoulder and permit the full delivery movement of the carriage to take place, the coins being deposited in the cash drawer prior to the completion of the delivery movement.

The merchandise, of any given kind, shape or size is stocked in separate columns within the case of the machine, and behind a glass plate.

40 Each column of merchandise is controlled by a separate carriage. The article just above the one being delivered is automatically held in place and prevented from dropping down upon the article being delivered by the 45 first part of the delivery movement of the carriage, and is not released till the completion of the return from the delivery movement.

50 My vending machine is described more in detail below and in the drawings, in which:—

Figure 1 is a partial elevation and fragmentary section through one unit of my vending machine.

Figure 2 is a fragmentary plan view of my vending machine showing the plan of one 55 unit.

Figure 3 is a fragmentary front elevation showing one end unit of my vending machine.

Figure 4 is a fragmentary elevation showing the slots of the coin slot plate. 60

Figure 5 is a section through the trigger guard of the coin plate on the line 5—5 of Figure 1.

Figs. 6 and 7 are detail views of the ejecting mechanism showing two positions of the 65 same.

The back 1 of the case is mounted by the hinges 2 to one end piece 3, and when closed is locked to the other end piece 3 by the locks 4, only one of which is shown. In fact, unless the case is quite high, one lock for the back 1 will probably be enough. 70

The back 1 is provided with a flange 5 which fits over the top 6, holding it closed.

When the back 1 is opened, the top 6 may 75 be raised, as it is hinged at either end to the end pieces 3 by the pins 7, only one of which is shown.

The top 6 is, at either end, provided with a flange 8, which fits outside the end piece 3. 80

Each end piece 3 is provided with a lug 9 to which is attached the tie band 10 by the screws 11.

Each end piece 3 is also provided with a lug 12, to which is attached the tie band 14 by 85 the screws 15.

Each end piece is also provided with the shelf 16, upon which slides the cash drawer 17, which is to be locked by the lock 18. 90

The delivery slide 19 is at each end provided with a flange 20, the screws 21 holding the delivery slide and the end pieces together, the end pieces acting to support the slide.

The slide, if desired, may be made of a 95 casting instead of formed sheet metal as shown.

The base plate 22 is provided with stud bolts 23 which pass through lugs 24 in the end pieces, 3 the nuts 25 holding the end pieces 100

firmly upon the base plate, and making the machine inaccessible from below.

The pedestal 26 is an integral part of the base plate 22; but in case the vending machine is placed upon a table or counter, the base plate 22 is to be made without the pedestal 26.

The coin slot plate 27 is held in place by the end pieces 3, by the screws 28 and by the flanges 29 of the end pieces 3.

10 The cash drawer 17 when closed covers the screws 28 so that they are inaccessible.

The flanges 29 of the end pieces 3, the top 6, and the coin slot plate 27, all combine to hold the glass merchandise cover plate, or 15 front plate 30 in place.

The merchandise is stocked in a column in each unit, between the glass front plate 30, the two division walls 31, and the division wall flanges 32.

20 The lowermost article of merchandise rests upon the tilting table 33, which is pivotally mounted upon the shaft 34, the heavier end 38 being normally held up so the table is horizontal by contact of the other end with 25 the locking wall 35 of the carriage platform 36, which joins the two carriage side bars 37.

Before going further into the description of the mechanism of the vending unit, it will now be seen that the service man may first 30 glance at the glass front plate 30 and at once perceive the amount of restocking required by the various columns.

He may unlock the cash drawer 17 and collect the coins therefrom, and then close and 35 re-lock the drawer.

He next unlocks and opens the back 1, which allows him to then raise the top 6, so 40 that he may replenish with new stock the stock column of each unit of the machine. He next closes the top, then closes and locks the back, and the servicing of the machine has 45 been easily and quickly accomplished.

The vending machine is all enclosed; there are no bolts, screws or other factors on its 45 exterior which would make it easy to be robbed by the amateur thief with a screw driver, wrench, or piece of bent wire.

Should a thief attempt to rob the machine by pulling the handle 39 without depositing 50 the required coins in the coin slots, the triggers 40 and 41, by contact with the locking shoulder 42, stop the movement of the carriage before the locking wall 35 has reached the pivot shaft 34 of the tilting table 33, so 55 that the table is still held horizontal, and the merchandise is still inaccessible.

The carriage rails 43 are provided with full length slots 44, and with grooves 45 in the upper face of the rails.

60 The carriage side bars 37 have turned out flanges which are received by and slide in the slots 44.

The carriage side bars 37 are riveted to the coin carriage 46 by the rivet 47. The coin carriage 46 is provided with the cylindrical

operating rod 48, upon which is secured the handle 39.

The carriage rails 43 are recessed to receive the coin delivery band 49, which is secured to the rails 43 by the screws 50.

The trigger shaft 51 is mounted in holes through the rails 43, the spacer sleeves 52 fitting over the shaft 51 and acting to properly position the triggers 40 and 41.

The return spring shaft 53, is mounted in holes in the rails 43, and the coin carriage shaft 54 is mounted in a hole through the coin carriage 46, these two shafts being joined by the tension return springs 55.

The slotted lever shafts 56 are mounted in holes in the rails 43 and carry the slotted levers 57, properly spaced by the sleeves 58 and held in place by the washers 59 and the cotter pins 60.

The coin carriage shaft 54 is received by 85 the slots of the slotted levers 57.

The merchandise stop 62, slideable in the grooves 45 of the rails 43, is connected to the slotted levers by the merchandise stop rods 61.

As the handle 39 is pulled, the carriage platform 36 moves under the rear of the article just above the one being delivered, which is supported by the tilting table 33; and at the same time, the merchandise stop 62, through action of the rods 61, slotted levers 57 and coin carriage shaft 54, is moved 90 backward and under the front end of the same article, thus effectively preventing it from dropping down upon the article being 100 delivered.

The curved lip 63 of the stop 62 provides a means of setting the machine for articles of different thicknesses, or permits the perfect setting of the machine for an article without slow, and costly changes in the proportions 105 of the machine.

The lip 63 is merely bent as required to the exact position where it will move in above the article being delivered, and below the 110 second article in the column.

It is evident that my vending machine may be used to vend articles with considerable range in cost by the employment of the proper number of coin slots of the proper size, and by making the rest of the machine to conform thereto.

However, for simplicity in explanation, the drawings, and this description deal only with a machine selling articles for fifteen cents, that is, requiring one five cent piece and one ten cent piece for its operation.

A nickel is placed in the slot 64 of the coin slot plate 27, and a dime is placed in the 125 slot 65.

The nickel falls into the nickel slot 67 and the dime falls into the slot 68 of the coin carriage 46, both coins then resting against the edge of the coin delivery band 49, the 130

nickel being shown at 71 and the dime at 72 in Figure 1.

In case an attempt is made to insert a penny in the dime slot 65 it will be found that the slot is too small to receive it.

5 If a penny is inserted in the nickel slot 64 it will fall straight through, as indicated at 73, Figure 1, and be returned down the delivery slide 19.

10 With both coins in the proper positions 71 and 72, the handle 39 is then pulled, and the coins ride up on the edge of the coin delivery band 49 to the positions shown at 74 and 75.

15 Further movement of the handle 39 forces the coins to contact with the bevels 69 and 70 of the triggers 40 and 41 respectively.

This raises the triggers against the pressure of the springs 78, till their lower corners 79 will clear the locking shoulder 42, of the coin carriage 46.

20 As the carriage continues its movement the coins are discharged into the cash drawer 17 as shown at 76 and 77, the action of the springs 78 assisting in this discharge.

25 Just after the discharge of the coins into the cash drawer, the locking wall 35 moved far enough to permit the tilting table 33 to revolve about the shaft 34, allowing the article to slide downward upon the table 33 and discharge upon the delivery slide 19.

30 When the handle 39 is released, the springs 55 return the entire carriage to its original position as shown in Figure 1, the slotted levers 57 and the merchandise stop rods 61 acting to return the merchandise stop 62 and release the front end of the second article, as the rear end of the article is released by the final return movement of the platform 36.

35 The second article, that is, the article next above the one just delivered, is thus allowed to drop down upon the tilting table 33, and the machine is ready for the next delivery.

40 It will be seen that because of the locking wall 35 keeping the table 33 horizontal, it is impossible to rob the machine without raising the triggers 40 and 41 to clear the locking shoulder 42.

45 And because of the trigger guard 66, and the stiff springs 78 and the angle of the trigger bevels 69 and 70, it is impossible even with a bent wire to raise the triggers so as to permit the full delivery movement of the carriage.

50 And because of the merchandise stop 62 and the platform 36 it is not only impossible to rob the machine by reaching up along the delivery slide 19 at the end of the delivery movement, but it is also impossible for more than one article to be delivered at each complete delivery movement of the carriage.

55 Also, if a nickel only, is inserted, the dime trigger 41 will contact with the locking shoulder 42, and prevent the carriage from making the full delivery movement. And, if a dime only, is inserted, the nickel trigger 40

will contact with the locking shoulder 42 and prevent the carriage from making the full delivery movement.

60 If the article is to sell for twenty cents, the machine will have two dime slots, triggers and complementary parts.

65 If the article is to sell for twenty five cents, a single slot, trigger, and complementary parts, adapted to take a twenty five cent piece, will be employed.

70 If the article is to sell for forty cents, there will be a twenty five cent piece slot, a nickel slot, and a dime slot, with all necessary complementary parts to go with same.

75 In other words, whatever the price of the article, the proper number and size of slots and other parts are to be used.

80 If all the merchandise in a given column has been sold, this will be perfectly apparent to any intending purchaser, due to the glass front 30; and because of the glass front the purchaser can choose the particular kind of article he desires, and then operate the corresponding unit of the vending machine.

85 I am well aware that there are numerous alterations which can be made in my vending machine which will not seriously affect it, nor depart from the essence of my invention.

90 I am also aware that there are various mechanical equivalents that may be used in the disposition of various bolts, screws, pins, rods, shafts, springs, and other parts.

95 So, I do not wish to limit my protection narrowly to the exact construction shown and described, but what I claim as new, and desire to protect by Letters Patent, is as follows:

1. In a coin operated vending machine having a case adapted to store vendible articles of merchandise in a laterally stationary vertical column behind a glass plate, a pivotally mounted table adapted to normally support said column and to deliver the lowermost article by pivotal movement of the table after a predetermined movement of said article along the table, and a manually operated carriage slidable above said table to a delivery position and having a platform adapted to contact with and move the lowermost article along the table and to slide under and support the next article thereabove and adapted by off-center contact with said table to prevent said pivotal delivery movement thereof prior to the completion of said predetermined movement.

105 2. In a coin operated vending machine having a case adapted to store vendible articles of merchandise in a laterally stationary vertical column behind a glass plate, a pivotally mounted table adapted to normally support said column and to deliver the lowermost article by pivotal movement after a predetermined movement of said article along the table, a manually operated carriage adapted

to give said article said predetermined movement and prevent the said pivotal movement of the table prior thereto and slidably above said table to a delivery position, and means carried by said carriage and adapted to move under the article next above the lowermost article and prevent its delivery therewith.

3. In a coin operated vending machine having a case adapted to store vendible articles of merchandise in a laterally stationary vertical column behind a glass plate, a pivotally mounted table adapted to normally support said column and to deliver the lowermost article by pivotal movement near the completion of a delivery movement of said article to a delivery position, a manually operated carriage adapted to move said article to said delivery position and means carried by said carriage adapted to move under the article next above the lowermost article and prevent its delivery therewith.

4. In a coin operated vending machine having a case adapted to store vendible articles of merchandise in a laterally stationary vertical column behind a glass plate, a pivotally mounted table adapted to normally support said column and to deliver the lowermost article by pivotal movement near the completion of a delivery movement thereof along said table to a delivery position, a manually operated carriage adapted to move said article to said delivery position, and means carried by the carriage and adapted to be moved thereby under the article next above the lowermost article and prevent its delivery therewith.

5. In a coin operated vending machine adapted to vend merchandise by a manually operated coin controlled delivery carriage, a pivotally mounted table adapted to normally support a laterally stationary column of articles of merchandise to be vended and a platform on the carriage normally spaced from the pivotal mounting of the table and contacting with the table to maintain it normally in the supporting position, and adapted to move under and support the said column above the lowermost article and to permit the tilting of the table and the delivery of merchandise, when by the movement of the carriage the platform becomes adjacent the pivotal mounting of the table.

6. In a coin operated vending machine adapted to vend merchandise by a manually operated coin controlled delivery carriage, a pivotally mounted table adapted to support a laterally stationary column of articles of merchandise to be vended, a lock on the carriage normally spaced from the pivotal mounting and contacting with the table to maintain it normally in the supporting position, and adapted to permit the tilting of the table and the delivery of the merchandise when the lock is moved by the movement of the carriage adjacent the pivotal mounting of the table, a

stop adapted to move under the article next above the one being delivered and prevent its being delivered therewith, means connecting the stop and the carriage and adapted to move said stop by the movement of the carriage, and a platform on the carriage adapted to be moved under the article next above the one being delivered, by the delivery movement of the carriage.

7. In a vending machine adapted to deliver one article of merchandise by each delivery movement of a manually operated, normally locked, and coin controlled carriage, a pivotally mounted table adapted to support a laterally stationary column of articles of merchandise to be vended, a locking platform on the carriage normally spaced from the pivotal mounting and contacting with the table to maintain it normally in the supporting position and adapted to permit the tilting of the table and the delivery of the article resting directly thereon when the locking platform is moved by the delivery movement of the carriage to the delivery position adjacent the pivotal mounting of the table and under the article next above the lowermost and stop means adapted to be moved by the movement of the carriage under the article next above the one being delivered, and thereby assist the locking platform to prevent its being delivered therewith.

8. The combination of a cabinet having a glass plate in one wall thereof and provided with a plurality of spaces for laterally stationary columns of merchandise behind the glass plate, a pivotally mounted table adapted to normally support each column of merchandise, a manually operated coin controlled delivery carriage adapted to deliver the lowermost article of each of said columns upon a delivery movement to a delivery position co-operating with each table, a platform on each carriage normally spaced from the pivotal mounting of its corresponding table and contacting with its table to maintain it normally in the supporting position and adapted to permit the tilting of the table and the delivery of the article resting directly thereon when the platform is moved by the delivery movement of the carriage to the delivery position adjacent the pivotal mounting of the table, and stop means adapted to be moved by the movement of each corresponding table under the article next above the one being delivered and thereby assist the platform to prevent its being delivered therewith.

In testimony whereof I affix my signature.
CHARLES H. CURTIS.
